UNITED STATES PATENT OFFICE.

ELIJAH CHETWYND, OF TRENTON, NEW JERSEY, ASSIGNOR TO JOHN MOSES,
OF SAME PLACE.

DESIGN FOR A DINNER OR TEA SET.

SPECIFICATION forming part of Design No. 13,005, dated June 27, 1882.

Application filed May 3, 1882. Term of patent 7 years.

To all whom it may concern:

Be it known that I, ELIJAH CHETWYND, a subject of the Queen of Great Britain, but residing at Trenton, in the county of Mercer and State of New Jersey, have invented and produced a new and original Design for Dinner, Tea, and Toilet Sets, of which the following is a specification.

My present invention consists in a design for dishes of various kinds, such as dinner, tea, and toilet sets, and including the handles, covers, and feet of such dishes, such design being neat, novel, and ornamental.

The accompanying photographic illustrations show a number of such dishes to which my design is applied.

The dish constructed in accordance with my design may have the general body thereof made in any ornamental outline shape, although I prefer the shape shown in the drawings, and presenting, when viewed from above, a dish with straight-lined sides and rounded ends, such ends, however, not presenting a purely semicircular form; but the curve, instead of being continued full and round to the side, is brought in more rapidly, and is turned into an inward-bending curve near each corner, and the line thus curved reaches the side at a nearly right angle therewith, thus forming four obtuse-angled corners. The covers of the dishes of course have a corresponding shape. These dishes are provided with feet having scallops circular in shape. The handles of these dishes and of their covers rise directly from the body and at right angles, or nearly so, thereto, and thus continue for a short distance, when a sharp bend is made and the parts approach each other at an angle obtuse in all the covered dishes and covers and unite in a circular boss in the center. This central boss is composed of a raised rim and raised center with depressed radial arms. Immediately within the raised rim, and connecting with the depressed radials, is a circular depression. The boss, being similar in shape upon each side, forms the central part of the handle. Upon the handle, commencing at this

raised rim and passing down the face of each side until near the dish or cover, is a flat depression, occupying about one-third of the 50 surface of such side.

I do not confine myself to handles of the exact angles shown, but preferably make them as shown, as combining the greatest degree of ornamentation with simplicity of form.

What I claim as my invention is—

1. A dish with straight-lined sides and rounded ends, the line of such ends rounding rapidly and passing near each side of the dish into an inward curve and meeting the side at 60 an obtuse angle, forming obtuse-angled corners, substantially as shown and described.

2. A dish with straight-lined sides and rounded ends, the line of such rounded ends rounding rapidly and passing near each side 65 of the dish into an inward curve and meeting the side at an obtuse angle, forming obtuse-angled corners, such dish having scalloped feet, all substantially as shown and described.

3. A design for a dish-handle, consisting of 70 short feet rising rectangularly out of the dish and making a sharp bend, continued toward each other at an angle indifferently large, until they meet and are connected by a central boss, substantially as shown and described.

4. A design for a dish-handle, consisting of the feet rising rectangularly out of the dish, thence approaching each other at an angle, united to and connected by a central boss, with rounded rim, radial arms, and elevated nave, 80 all substantially as shown and described.

5. A design for a dish-handle, consisting of the feet rising rectangularly out of the dish, thence approaching each other at an angle and bearing upon their sides a longitudinal flat depression, and united to and connected, by a central boss, with rounded rim, depressed radial arms, and elevated nave, all substantially as shown and described.

ELIJAH CHETWYND.
